(57) **CLAIM**

The ornamental design for a cap for dispensing tube, as shown and described.

DESCRIPTION

FIG. 1 is a bottom, left, frontal perspective view of our invention;

FIG. 2 is a top, left, frontal perspective view thereof;

FIG. 3 is a front, rear, left side, and right side elevational view thereof;

FIG. 4 is a top plan view thereof; and,

FIG. 5 is a bottom plan view thereof.

In a preferred embodiment the cap is useful for controlling dispensing of an insecticidal baiting compound from a squeeze tube containing that composition.

The broken line representations of threads and other internal structures in FIGS. 2 and 4, a lower closure end in FIGS. 1 and 5, and support ribs in FIGS. 1-3, are for purposes of illustration only and form no part of the claimed subject matter.

In a preferred embodiment the cap is useful for controlling dispensing of an insecticidal baiting compound from a squeeze tube containing that composition.
